GRATE-SUPPORTING STRUCTURE

Charles A. Sleicher, Providence, R. I., assignor to
 New England Butt Company, Providence, R. I.,
 a corporation of Rhode Island

Application March 5, 1943, Serial No. 478,101

1-Claim. (Cl. 126—176)

The present invention relates to a structure for mounting grate-bars above the ash-pit of a boiler, furnace, or the like and more particularly to a supporting frame for the grate which is adjustable to conform to practically any size and shape of ash-pit.

In most coal-burning boiler and furnace installations the grate-bars are mounted in bearing-brackets built into the side walls of the ash-pit. In many instances, such coal-burners have been converted to burn fuel-oil by removing the grate-bars and substituting oil-burning apparatus. When such coal-burning installations are converted to burn oil the grate-bars are usually removed and discarded so that they are not available for later use. Also, when converting from coal to oil the bearings for the grate-bars built into the sides of the ash-pit are usually cut away and the pit lined with fire-brick, cement or other refractory material to protect its sides against direct contact by the oil flame. In such cases, even though the original grate-bars are saved, they cannot be replaced in the fire-box. When boilers or furnaces are originally installed for burning fuel-oil no provision is made for supporting a grate for the fire-box. Due to the present shortage of fuel-oil it is desirable to convert many of such oil-burning boilers and furnaces to burn coal and the present invention provides a convenient and relatively inexpensive means for this purpose.

One of the objects of the present invention is to provide a structure for supporting the grate-bars of furnaces and boilers which is independent of the apparatus originally installed and adjustable for use in ash-pits of substantially all sizes and shapes.

Another object is to provide a structure of the type indicated having rails extending longitudinally at opposite sides of the ash-pit and provided with bearings arranged in equidistantly spaced relationship therealong for pivotally mounting the ends of the grate-bars.

Another object is to provide a structure of the type indicated with composite rails made up of the required number of sections to give an additive length corresponding to the length of the ash-pit.

Another object is to provide a structure of the type indicated in which the rails are adjustable vertically on supporting legs to position the grate-bars at the proper level in the bottom of the fire-box.

Another object is to provide a structure of the type indicated having sectional spacer-bars or

girts extending between the rails and adjustable longitudinally to adapt the frame for ash-pits of different widths.

Another object is to provide a frame of the type indicated which is of simple and compact construction and composed of unmachined castings to adapt it for economical manufacture.

Further objects of the invention are set forth in the following specification which describes a preferred form of grate-supporting structure, by way of example, as illustrated by the accompanying drawings. In the drawings:

Fig. 1 is a plan view of a grate-supporting structure incorporating the novel features of the present invention and showing the longitudinally-adjustable spacer-bars or girts for maintaining the side rails in spaced relationship abutting the side walls of the ash-pit;

Fig. 2 is an elevational side view of the grate-supporting structure showing the composite construction of the side rails and the means for adjusting the rails on their supporting legs to position the grate-bars at the proper level in the fire-box;

Fig. 3 is a transverse sectional view on line 3—3 of Fig. 2 showing the ends of a grate-bar pivotally mounted in the side rails of the supporting structure;

Fig. 4 is an enlarged sectional view on line 4—4 of Fig. 2 showing the bolts for connecting the legs to the brackets depending from the rail-sections and the tongue-and-groove construction of the legs and brackets for holding the legs against pivotal movement;

Fig. 5 is an enlarged transverse sectional view on line 5—5 of Fig. 1 showing the manner in which the overlapping complementary portions of the spacer-bar or girt sections are bolted together in adjusted relationship and illustrating the recesses in the complementary portions for receiving the heads and nuts of the connecting bolts;

Fig. 6 is an enlarged transverse sectional view on line 6—6 of Fig. 1 showing the interlocking key-and-slot connection between the end of the girt and the bearing-cap for preventing rotation of the girt; and

Fig. 7 is a perspective view showing the ends of two adjacent rail-sections with the parts in disassembled relationship.

Referring to the drawings, the grate-supporting structure or frame of the present invention is adapted for use with practically all types of furnaces and boilers having the usual front plate 2 with a fire-door 3 and ash-pit door 4. The

grate-bar supporting frame consists of horizontal rails 5 and 6 adapted to extend longitudinally of the ash-pit at opposite sides thereof. The rails 5 and 6 are of composite construction comprising a plurality of complementary sections 7 of identical form and length adapted to be connected to each other at their ends. Each section 7 has a rectangular body portion, see Figs. 3 and 7, with semicircular grooves or bearing recesses 8 in its top arranged in equidistantly spaced relationship along its length, and depending leg-brackets 9, usually three in number, offset inwardly from one side of the rail as shown most clearly in Fig. 3. The depending leg-brackets 9 are of channel-shape in cross-section with spaced flanges 10 and 11 projecting at one side and bolt-holes 12 positioned midway between the flanges.

Each section 7 has an extension or ear 15 at one end projecting longitudinally beyond its body portion and offset laterally thereof with a flat face on one side and a channel or slot 16 on its opposite side, see Fig. 7. The ear 15 is of a length corresponding to the distance between the centers of two adjacent bearing recesses 8 and is provided with an arcuate recess 13 at its inner end which forms a continuation of a similar arcuate recess in the end of the body portion of the rail to provide a semicircular bearing at the point of joinder of the sections. The ear 15 also has an arcuate recess 14 at its outer end for cooperation with the recess 13 at the end of the body portion of another section to which it may be connected, whereby to form the next adjacent bearing recess at the joinder of the sections. Each section 7 has an ear 17 projecting longitudinally from its opposite end and offset inwardly from the side of the body portion. The ear 17 also is provided with arcuate recesses at its outer and inner ends adapted to aline respectively with the arcuate recess 13 at the inner end and the recess 14 at the outer end of the ear 15 on the next adjacent section connected thereto; thereby providing properly spaced semicircular bearing recesses in the connected portions of the rail-sections as shown in Fig. 2. The ears 15 and 17 on adjacent rail-sections 7 are thus complementary to adapt them to overlap in the manner illustrated in Fig. 1, being provided with alined holes 18 and 19 through which bolts 20 are inserted to connect adjacent sections. The bolt-heads 21 are located in the channeled slot 16 on the side of the ear 15 to hold them from turning and the nuts 22 on the threaded ends of the bolts are set up against the flat side of the ear 17 underlying the side of the rail to permit the latter to closely abut the side of the ash-pit.

Each composite rail 5 or 6 may be made up of the proper number of connected sections 7 to give an additive length corresponding to the length of the ash-pit and fire-box. The ear 15 at the end of the rearmost rail-section 7 may be cut off and any portion of the foremost section which would project beyond the front of the ash-pit also may be cut away so that the composite rail will fit closely between the forward and rearward ends of the ash-pit. The composite rails 5 and 6 will then have the same length and be positioned at opposite sides of the ash-pit with the corresponding bearing recesses 8 of the opposite rails in alinement.

Each rail 5 or 6 is supported by a series of vertical legs 23 which are attached to the depending leg-brackets 9 on the rail-sections 7

in the manner as next explained. The legs 23 have feet 24 at their lower ends adapted to rest on the floor 25 of the ash-pit which may be of concrete, masonry or the like. The legs 23 are of rectangular shape in cross-section, of the proper width to adapt them to fit closely between the flanges 10 and 11 on the depending leg-brackets 9 and of a thickness corresponding to the offset of the leg-brackets from the outer side of the rails to adapt them to aline therewith, see Fig. 3. As illustrated in Figs. 2 and 7, each leg 23 has a central slot 26 with a recess 27 at the side thereof extending throughout a considerable portion of its length. The legs 23 are attached to the depending leg-brackets 9 by means of bolts 28 extending through the slots 26 in the legs and the holes 12 in the depending leg-brackets 9, the heads of the bolts being positioned in the recesses 27 to hold the bolts against turning movement while enclosing the heads wholly within the confines of the legs. By loosening the nuts 29 on the bolts 28 the rails 5 and 6 may be adjusted vertically on the legs 23 to level the rails at the proper height for supporting the grate-bars at the bottom of the fire-box.

The rails 5 and 6 are adapted to abut closely against the side walls of the ash-pit, see Figs. 1 and 3, being held in their spaced relationship by means of adjustable spacer-bars or girts 31 and 32 at the front and rear. The girts 31 and 32 are of generally rectangular shape in cross-section with reduced cylindrical projections 33 at their ends for mounting them in alined bearing recesses 8 at the ends of the opposite rails 5 and 6. The shoulders 34 surrounding the projections 33 at the ends of the girts 31 and 32 engage against the inside faces of the rails 5 and 6 as shown in Fig. 1 to hold the latter in their spaced relationship and the projections have rectangular lugs 35 which cooperate with correspondingly-shaped slots 36 in recessed bearing-caps 49, later to be described, to hold the spacer-bars from turning, see Figs. 2 and 6.

The girts 31 and 32 are preferably so constructed as to adapt them for longitudinal expansion or contraction to locate the rails 5 and 6 in their proper spaced relationship in ash-pits of different widths. As illustrated in Figs. 1 and 5, the girts 31 and 32 are of composite construction, each comprising a pair of complementary members 37 of identical form. Each member 37 has a rectangular body portion with its end opposite the end having the cylindrical projection 33 recessed on one side throughout a considerable distance to provide a longitudinal extension 38 of reduced width. The extension 38 of each member 37 is provided with a slot 39 reaching throughout a considerable portion of its length and the side of the extension flush with the body portion of the member is provided with a slotted recess 40 surrounding the slot. A pair of the members 37 may be placed in reversed relationship so that their extensions 38 overlap, that is with the extension of each member positioned in the recessed portion of the opposite member. The pair of reversed members 37 may then be connected by means of bolts 41 projecting through the slots 39 in the overlapping extension 38, the heads 42 of the bolts and the nuts 43 on their ends being located in the recesses 40 surrounding the slots. The recess 40 at one side prevents the bolts 41 from turning and their heads 42 and nuts 43 are contained wholly within the confines of the composite girts 31 and 32 to

avoid projections along the sides thereof. By loosening the nuts 43 on the bolts 41 the members 37 may be slid relatively of each other to lengthen or shorten the girts to adjust the rails 5 and 6 to correspond to the width of the ash-pit. In instances where the ash-pit is of extreme width the members 37 of the girts 31 and 32 may be placed with their extensions 38 in alinement and an auxiliary bar bolted thereto to splice the sections together at greater length.

The grate-bars 46 may be of any usual construction with their ends mounted in the recesses on the side rails 5 and 6 to adapt them for rocking motion to shake the grate. As herein illustrated, each grate-bar 46 comprises a central rod-like portion with closely adjacent parallel lugs 47 projecting laterally from either side thereof. At their ends the grate-bars 46 have cylindrical bearing trunnions 48 for seating in the alined bearing recesses 8 in the opposite rails 5 and 6 to mount them for rocking motion. As shown in Fig. 1 of the present drawings, each grate-bar 46 is of a width slightly less than twice the distance between the centers of two adjacent bearing recesses 8, thereby permitting an arrangement of the grate-bars in alternate bearing recesses to utilize the maximum grate surface in the fire-box for different conditions. In other instances, where interlocking grate-bars are to be used, their trunnions may be seated in the whole number of the bearing recesses.

A cap 49 is provided for each rail-section 7 for seating on the top thereof, each cap having bearing recesses 50 therein for cooperating with the bearing recesses 8 in its related rail-section. The trunnions 48 at the ends of the grate-bars 23 are thus enclosed in the bearings to restrain the bars against lifting or becoming displaced. One or more of the recesses 50 in each cap 49 may be provided with a key slot 36, previously referred to, for receiving the lugs 35 at the ends of the girts 31 and 32. The bearing caps 49 are held in position on the rail-sections 7 by means of bolts 51 extending therethrough and fastened by nuts on the under side of the rails.

The grate-bars 46 may be provided with laterally spaced pairs of depending arms 52, 53 and 56, 57 for connection with one or the other of a pair of shaker-bars 58 and 59. Preferably, the shaker-bar 58 is positioned between and connected to the depending arms 52 and 53 of alternate grate-bars 46 by means of bolts or pins 60. As herein shown, the second shaker-bar 59 is positioned between and connected to the arms 56 and 57 of the remaining grate-bars 46 by means of pins 60. The grate-bars 46 are usually cast with both pairs of depending arms 52, 53 and 56, 57 at one end and such arms as are not used may be cut off to provide the whole set of bars with alternating arms. For exceptionally long fire-boxes a second set of grate-bars 46 may be provided arranged in reversed end-for-end relation to the first set to position the depending arms 52, 53 and 56, 57 at the opposite side of the ash-pit for connection to a second pair of shaker-bars 61 and 62 which may be attached respectively to the arms 52, 53 and 56, 57 of alternate grate-bars, see Figs. 1 and 3. The shaker-bars 58, 59 and 61, 62 extend forwardly through the front plate 2 of the furnace and are connected to the lower end of levers 63 pivoted intermediate their ends in bearing-brackets 64 on the front plate 2. A lever 63 is provided for each shaker-bar and is usually

adapted to receive a handle for oscillating it to reciprocate the bar to rock the grate-bars connected thereto. One preferred form of construction incorporating the novel features of the present invention having been described in detail, the manner of assembling the parts in the ash-pit of a furnace or boiler and the method of operation of the assembly is as next explained.

When installing the grate-bar supporting structure the length of the ash-pit is measured and the required number of rail-sections 7 are connected at their ends to give an additive length corresponding thereto. The ear 15 on the rear-most rail-section 7 usually is removed and the complementary ears 15 and 17 on adjacent rails are brought into overlapping relationship to aline their bolt-holes 18 and 19. The sections 7 of the rails 5 and 6 may be assembled outside of the ash-pit but preferably, due to their weight, they are assembled within the pit. The adjacent sections 7 are connected by inserting the bolts 20 through the alined holes 18 and 19 in the ears 15 and 17 and screwing the nuts 22 onto the threads of the bolts to set them up against the side of the ear 17. The heads 21 of the bolts 20 are positioned in the channeled slot 16 and the nut 22 on the ends of the bolts, when set up against the side of the ear 17, will be positioned wholly within the confines of the rails so as not to project laterally therefrom. If the rails 5 and 6 have the minimum number of rail-sections 7 necessary to extend throughout the length of the ash-pit and are found to project somewhat therefrom at the front, the excess length of the foremost sections may be cut off as indicated in Fig. 2. In other instances, it may be found advantageous to remove the excess length from the rearmost sections 7. In this manner two composite rails 5 and 6 may be built up of connected sections 7 to aline their corresponding bearing recesses 8 on opposite sides of the ash-pit.

The rail-sections 7 are preferably mounted on the legs 23 as they are assembled in the ash-pit. For this purpose each leg 23 is positioned between the flanges 10 and 11 on the outer side of a leg-bracket 9 and the bolts 28 inserted through the slot in the leg and the holes 12 in the bracket. The nuts 29 are screwed onto the threaded ends of the bolts and set up against the inner side of the leg-bracket as shown in Fig. 3. It will be observed from this view that the heads of the bolts 28 then will be positioned wholly within the recess 27 in each leg 23 so that the outer side of the leg will be flush with the outer side of the rail-section 7 to permit the rails 5 or 6 to abut closely against the side walls of the ash-pit. In attaching the legs 23 to the brackets 9 the rail-sections 7 are raised sufficiently to position the grate-bars 46 to be mounted thereon at the proper height in the fire-box before the nuts 29 are tightened on the bolts 28, the slots 26 in the legs permitting such vertical adjustment of the rail-sections to bring them into alinement and level them notwithstanding any irregularities on the floor of the ash-pit.

After all the rail-sections 7 have been assembled and mounted on the legs 23 the girts 31 and 32 may be connected to the opposite rails 5 and 6 by seating the terminal projections 33 on the girts in the alined bearing recesses 8 at the forward and rearward ends of the rails. The girts 31 and 32 may be adjusted in length to adapt them to extend across the ash-pit by loosening the nuts 43 on the bolts 41 and sliding their extensions 37 relatively to each other until the shoulders 34

at their ends engage against the inner sides of the rails 5 and 6. After the girts 31 and 32 have been properly adjusted the nuts 43 on the bolts 41 are tightened to rigidly connect the two sections 31 of each girt and brace the rails 5 and 6 against the sides of the ash-pit.

After the supporting structure has been assembled in the manner explained above, the grate-bars 46 may be mounted in their alined bearing recesses 8 on the rails 5 and 6 by seating their trunnions 48 therein as shown in Figs. 1 and 2; the entire area between the rails being filled with the grate-bars. As the bearing recesses 8 in the rails 5 and 6 are spaced apart a distance equal to half the width of a grate-bar 46, the first or end grate-bar can be mounted in the pair of alined bearing recesses nearest the end of the ash-pit since the rails may be made to extend the entire length of the fire-box within the limits of one-half the width of a grate-bar. After all the grate-bars 46 have been mounted on the rails 5 and 6 the caps 49 are fastened in place on the rail-sections 7 with their recesses cooperating with the bearing recesses 8 to adapt them to enclose the trunnions 48. The caps 49 are attached to the rail-sections 5 and 6 by means of the bolts 51 as previously explained.

In mounting the grate-bars 46 on the rails 5 and 6 certain of them are preferably reversed end-wise in relation to the others to position their depending arms 52, 53 and 56, 57 adjacent the opposite rails 5 and 6. In the embodiment of the invention illustrated in the present drawings, the forward set of grate-bars 46 have the arms 52, 53 and 56, 57 depending at the left-hand side of the ash-pit adjacent the rail 5, see Fig. 3; while the rearward set of grate-bars will have their depending arms adjacent the right-hand side of the ash-pit adjacent the rail 6. The depending arms 52, 53 or 56, 57 on alternate grate-bars may be removed so that the arms of adjacent grate-bars will be arranged in staggered relationship. The depending arms 52, 53 of the first, third, fifth, etc. grate-bars 46 of the forward set are connected to the shaker-bar 58 by means of the pins 60 while the alternate grate-bars 46, the second, fourth, sixth, etc. are connected to the shaker-bar 59. The first, third, fifth, etc. series of grate-bars 46 of the rearward set are connected to the shaker-bar 61 while the alternate grate-bars of this set are connected to the shaker-bar 62. With such a construction and arrangement of the grate-bars 46 the operator may shake the forward set of grate-bars by oscillating the levers 63 to reciprocate the shaker-bars 58 and 59 in opposite directions while the rearward set of grate-bars may be

shaken by operating the levers 63 for the shaker-bars 61 and 62. During such rocking of the grate-bars 46 they will rotate in the bearing recesses 8 in the rails 5 and 6 while being prevented from rising from the rails by the caps 49 which overlie their trunnions 48.

It will be observed from the foregoing specification that the present invention provides a structure independent of the original installation of a furnace or boiler for supporting grate-bars in the fire-box thereof whatever its size or shape. By connecting the proper number of rail-sections, composite rails having an additive length equal to the length of the ash-pit may be assembled, and by adjusting the rails on their supporting legs the grate-bars may be located at the proper height in the fire-box. By adjusting the spacer-bars or girts connecting the side rails, the latter may be held in their proper spaced relationship and braced against the walls of the ash-pit whatever its width within reasonable limits.

While one preferred form of the grate-supporting structure is illustrated and described herein, it is to be understood that modifications may be made in the construction and arrangement of its parts without departing from the spirit or scope of the invention. Therefore, without limiting myself in this respect, I claim:

In a grate-bar supporting structure adjustable 30 in length and width to conform to the varying dimensions of different sizes of boilers and furnaces, the combination of a plurality of relatively short rail-sections formed with bearing sockets for the ends of a series of grate-bars, offset 35 flanges at the opposite ends of said rail-sections provided with holes for receiving bolts for fastening said sections together in alinement; said flanges also formed with mating recesses adapted to aline when the flanges are bolted together to 40 form sockets for receiving the ends of certain of the grate-bars in the series and to cooperate with the sockets in the main lengths of the sections whereby to space the grate-bars equidistantly along the full length of a plurality of said 45 sections connected together in alinement, adjustable girts comprising telescopic members adapted to be fastened together to provide different overall lengths and having means for fastening their ends to the assembled rail-sections 50 to space them apart at distances conforming to different widths of grates, a leg on each of the rail-sections, and feet adjustable vertically on the legs to support the individual rail-sections and level them in alinement irrespective of irregularities in the floor of the ash-pit beneath the 55 boiler or furnace.

CHARLES A. SLEICHER.
